UNITED STATES PATENT OFFICE.

HERMAN SCHWARZE AND FENN M. HOLDEN, OF PONTIAC, MICHIGAN, ASSIGNORS TO
GENERAL MOTORS CORPORATION, OF DETROIT, MICHIGAN, A CORPORATION OF
DELAWARE.

LOCK-CONTROLLED SWITCH SYSTEM.

Original application filed September 6, 1921, Serial No. 498,931. Divided and this application filed
February 7, 1927. Serial No. 166,503.

This invention relates to lock controlled electric switches and the particular form of embodiment of the invention described hereinafter is an improvement on switches of the type disclosed in the patent to Kaisling No. 1,193,698, August 8, 1916. In the apparatus disclosed in the patent referred to a lighting switch includes a lever operable to several positions to control various lighting circuits of an automobile, and includes a lock for locking the lever in any of its positions either on or off.

In the present invention the general object is to provide an automobile lock switch controlling circuits in such a manner that the lighting of the car to comply with the law will not depend entirely on the memory of the driver. In carrying out this object we have provided that in order to find the key hole of the switch lock, the dash lamp and rear lamp may be lighted before the switch is unlocked; and that thereafter when the light switch is unlocked, the front lights will be automatically connected with the battery.

Other and further objects of the present invention will be apparent from the following description, reference being had to the accompanying drawings, wherein a preferred embodiment of the present invention is clearly shown.

In the drawings:

Fig. 1 shows diagrammatically a plan of the switch embodying the present invention together with a wiring diagram of an ignition circuit and other electrical translation circuits; and

Figs. 2, 3 and 4 are diagrammatic views of certain parts shown in Fig. 1, showing these parts in various positions.

Referring to the drawings, a support 20 carries stationary contacts 21, 22, 23 and 24 connected respectively with grounded electrical translation circuits 25, 26, 27 and 28. Circuits 25, 26 and 27 include various lighting circuits of an automobile, and circuit 28 includes the ignition apparatus for the automobile engine (not shown). A movable switch contact 29 is rotatably supported by support 20 and is moved by lever 30. Contact 29 includes fingers 31 and 32. Contact

29 is connected by wire 33 and wire 34 with grounded battery 35.

To index the contact 29 in its various positions, a plate 36 having spaced lobes or lugs 37, 38, 39, 40 and 41 is provided. Plate 36 is attached to lever 30 so as to be rotated thereby when contact 29 is moved.

Ignition switch contact 46 is rotatably supported by support 20 and is actuated by lever 47. To index contact 46 in its positions, a plate 42 is provided with spaced lobes or lugs 43, 44 and 45.

Lever 50 is slidably and pivotally mounted on pin 51 secured to support 20 and carries rollers 52 and 53 cooperating with plates 36 and 42 respectively. Spring 54 bears at one end against lever 50 and is attached at the other end to a lug 55 carried by support 20, whereby yieldingly to maintain rollers 52 and 53 in engagement with said plates 36 and 42 respectively.

Locking bolt 60 is slidably mounted upon support 20, said support carrying studs 61 and 62 extending through slots 63 and 64 respectively provided in bolt 60. Bolt 60 is provided with lug 65 adapted to enter the notch 66 between lugs 37 and 41 of plate 36 or the notch 67 between lugs 40 and 41. Bolt 60 is provided with lug 68 adapted to enter the notch 69 between lugs 43 and 45 of plate 42. Obviously the bolt cannot be moved to locking position unless the contact 46 is in off position as shown in Fig. 1.

The bolt 60 is actuated by a key operated locking cylinder 70 journalled in a support 71. Cylinder 70 carries a pin 72 for engaging a stud 73 carried by bolt 60. As shown in Fig. 1, bolt 60 is in unlocked position, but one counter clockwise turn of cylinder 70 will cause pin 72 to move bolt 60 to locked position shown in Figs. 2 and 3.

Starting with the bolt 60 in locked position, as shown in Fig. 2, ignition switch contact 46 will be locked since lug 68 will then be located in notch 69 of plate 42. The switch contact 29 may, however, be moved from the off position to its second position of adjustment, or to its first circuit making or on position as shown in Fig. 3. This is possible since notch 66 is wide enough to permit

finger 31 to engage contact 21 before lug 65 is struck by lug 41. When this occurs, the dash lamp or instrument board lamp of the automobile will be connected with the battery 35, thus enabling the driver to find the keyhole in the locking cylinder 70 after dark.

Referring to Fig. 3, when contact 29 has been moved into its first on position, the detent roller 52 will be in the position shown 10 wherein it has ridden over the point of lobe 39 and part way down onto the beveled camming surface 39^a. When the bolt 60 is moved into unlocked position shown in Fig. 4, the roller 52, being urged by spring 54 against 15 the surface 39^a, will exert a pressure in such a direction as to produce clockwise rotation of contact 29 so as to bring finger 31 into engagement with contacts 21 and 22. In this manner the automobile side lights will be 20 automatically turned on. Therefore the driver need not remember to turn on the side lights to comply with the city driving ordinances.

The fact that the driver cannot see the keyhole after dark makes him operate the switch lever to obtain light at the keyhole. Since the rear lamp is on the same circuit with the dash lamp, the rear lamp will inadvertently be turned on. The unlocking of the ignition 25 switch lever in order that the engine may be started turns on the side lights. Therefore the external lighting of the automobile becomes automatic depending on the unlocking of the ignition switch after dark.

35 It is advantageous to place the rear lamp on the dash lamp circuit for in some places the lighting of the rear lamp only is necessary for parking. Locking the light switch so that the side and head lights cannot be 40 turned on without authority prevents waste of battery current by meddlers.

By turning the contact 29 to its third on position when the roller 52 will engage in the notch between lobes 37 and 38, causes finger 31 to disengage contact 22 and to engage contact 23 to connect the head lamps with the battery; and finger 32 will then engage contact 21 but not contact 22.

The ignition switch will be held resiliently 50 in its off position, as shown in Fig. 1, by the engagement of the roller 53 in the notch between lugs 44 and 45, and in the on position by the engagement of the roller in the notch between lugs 43 and 44. While the form of 55 mechanism herein shown and described constitutes a preferred form of embodiment of the invention, it is to be understood that other forms might be adopted, all coming within the scope of the claims which follow.

60 This application is a division of application Ser. No. 498,931, filed September 6, 1921 (now Patent No. 1,635,226, issued July 12, 1927).

We claim:

65 1. In an electric system, the combination of

a control element, a lamp, a circuit for said lamp controlled by said element, other mechanism also controlled by said element, and a lock for said element arranged to be illuminated by said lamp, the parts being constructed and arranged to permit the element to be moved to a position for lighting said lamp before unlocking the lock.

2. In an electric lighting system for automobiles, a dash light, side lights and headlights, a switch for controlling the circuits to said lights, contacts for said circuits, the contacts so arranged that the dash light may be lighted alone or in conjunction with either the side lights or headlights, and a lock for said switch adapted when locked to permit the switch to be moved to light the dash light before the lock is unlocked but preventing the further movement of the switch to light any of the other lights mentioned.

3. In an electric system, the combination of a switch, a lock therefor, and means for illuminating said lock, said switch having a neutral position, a second position in which it causes actuation of said illuminating means, and a third position controlling other translating devices, and said lock arranged to permit, when in the locked position, movement of said switch from said neutral position to said second position but prevent movement to said third position.

4. In an electric system for use with internal combustion engines, a combined control mechanism comprising an ignition switch, an electric lamp, a lighting switch controlling the supply of current to said lamp and a lock for both switches, said lighting switch having an off position, a first circuit closing position in which it is adapted to control the illumination of the lock, and a second circuit closing position in which it is adapted to control other circuits, said lock constructed and arranged to prevent movement of said ignition switch and to permit movement of said lighting switch to said first position while preventing movement to said second position.

5. A lock switch comprising a switch member, a lock therefor and means for illuminating said lock, said member having an off position and a plurality of circuit closing positions, the switch in the first circuit closing position being arranged to cause lighting of said illuminating means, and the lock arranged to permit, when in locking position, the movement of the switch member to the first circuit closing position while preventing movement to other circuit closing positions.

6. In an electric lighting system the combination with a switch having a plurality of circuit closing positions, a lock for said switch adapted when in locked position to permit moving said switch from the off position to one of said circuit closing positions but preventing its movement to a second circuit closing position, a lamp controlled by said switch

- in said first position, and an additional lamp or lamps controlled by said switch in said second position, said switch adapted to move automatically from said first to said second 5 position when unlocked.
7. In an electric lighting system for vehicles, a switch having a first and a second circuit closing position, means for locking said switch adapted when in locked position to permit the switch to be moved from the off position to the first circuit closing position but preventing movement to the second circuit closing position, a lamp for illuminating the switch arranged to be lighted by movement of 10 said switch to said first position, and lamps for the exterior of the vehicle arranged to be lighted by movement of said switch to said second position, said switch adapted to move automatically from said first to said second 15 position when unlocked.
8. In an electric system, the combination with a switch having a plurality of circuit-closing positions, means for locking said switch adapted, when in locked position, to permit the switch to be moved from "off" position to a first circuit-closing position but preventing movement to a second circuit-closing position, means for illuminating said 20
- locking means arranged to be operated by movement of said switch to said first position and other translating means arranged to be operated by movement of said switch to said second position, said switch arranged to move automatically from said first position to said second position upon unlocking said 25 locking means.
9. An electric lighting system for vehicles comprising a switch having a plurality of circuit-closing positions, means for locking said switch adapted, when in locked position, to 30 permit movement of said switch from "off" position to the first circuit-closing position, means for moving said switch automatically from said first circuit-closing position to a second circuit-closing position upon movement of said locking means to unlocked position, a dash lamp arranged to be lighted by movement of said switch to said first position and other vehicle lamps arranged to be lighted by movement of said switch to said second 35 position.
- In testimony whereof we affix our signatures.

HERMAN SCHWARZE.
FENN M. HOLDEN.
